(57) **CLAIM**

The ornamental design for a radio control panel in a vehicle,
substantially as shown and described.

DESCRIPTION

FIG. 1 is a perspective view of the radio control panel in a vehicle design;

FIG. 2 is a front view thereof;

FIG. 3 is a rear view thereof;

FIG. 4 is one narrow side view thereof;

FIG. 5 is an opposite narrow side view thereof;

FIG. 6 is one broad side view thereof;

FIG. 7 is an opposite broad side view thereof;

FIG. 8 is a view to indicate example locations of the claimed design in a vehicle; and,

FIG. 9 is a view to indicate example locations of the claimed design in a vehicle.

In the drawings, the broken lines depict unclaimed environmental subject matter.
